[57] CLAIM

The ornamental design for a fish hook and leader holder, as shown and described.

DESCRIPTION

FIG. 1 is a top perspective view of a fish hook and leader holder showing my new design;

FIG. 2 is a front elevational view thereof;

FIG. 3 is a rear elevational view thereof; and

FIG. 4 is a top plan view thereof.

The dotted lines shown in FIG. 2 are for illustrative purposes only and form no part of the claimed design.
